UNITED STATES PATENT OFFICE.

CHARLES I. MANDEL, OF NEW YORK, N. Y.

COLLAR.

No. 927,257.

Specification of Letters Patent.

Patented July 6, 1909.

Application filed October 9, 1908. Serial No. 456,969.

To all whom it may concern:

Be it known that I, CHARLES I. MANDEL, a citizen of the United States of America, residing in New York, in the borough of Brooklyn, county of Kings, and State of New York, have invented certain new and useful Improvements in Collars, of which the following is a specification.

This invention relates to certain improvements in collars, and more especially to folding collars for men's and women's wear, in which by means of a reinforcing seam at the lower part of the multiply-top and a multiply-neck-band a narrow portion of less thickness is formed between the reinforcing seam of the top and the neck-band, so that the folding over of the top is greatly facilitated and a folding collar obtained which will be more convenient in use as it provides a groove that acts as a guide for the folding over of the top on the band.

The invention consists of a folding collar in which the neck-band is made of three or more plies and the folding top of four or more plies and provided at some distance from the upper edge of the neck-band with a reinforcing seam which forms between the seam and upper edge of the neck-band a narrow connecting portion of less thickness for the convenient folding over of the top part on the neck-band.

The invention consists further of certain additional details of construction which will be fully described hereinafter and finally pointed out in the claims.

In the accompanying drawings, Figure 1 represents a side-elevation of my improved folding collar before folding the top-part over the neck-band, Fig. 2 is a similar elevation of a modified construction of the collar, Figs. 3 and 4 are vertical transverse sections respectively on lines 3, 3, of Fig. 1; and 4, 4, of Fig. 2, drawn on a larger scale, and Fig. 5 is a vertical transverse section of the collar with the reinforced top part folded over, also drawn on a larger scale.

Similar letters of reference indicate corresponding parts throughout the different figures.

Referring to the drawings *a* represents the neck-band, and *b* the folding top of my improved collar. The neck-band is preferably made of three layers or plies, two at the outside and one at the inside, but any other number of layers or plies may be used so that the required stiffness of the neck-band is ob-

tained. The neck-band is made curved, so as to be readily shaped to fit around the neck of the wearer.

The top-part *b* is preferably made of four layers or plies, two outside or face-layers and two inside-layers. The inside layers *b*¹ are turned in at their upper edges and stitched to the face-layers by the usual line of stitches *b*² which extends also along the ends of the top. The folding top *b* is cut on a curved line corresponding with the curve of the neck-band. The inner layer or ply adjacent the inner face-layer is turned up above the neck-band and stitched by two lines of stitches *b*³ to the inner face-layer of the top, as shown in Figs. 1 and 3, so as to form a reinforcing seam. The other inner layer *b*¹ and the face-layers are extended into the upper edge of the neck-band and stitched to the same at *a*¹. Between the reinforcing seam and the upper edge of the neck-band a narrow connecting portion *d* of less thickness than the top is thus obtained. In place of forming the reinforcing seam of the top in the manner shown in Fig. 3, the outer face-layer can be turned in and stitched by two lines of stitches to the inner-layer or ply, as shown in Figs. 2 and 4, so that in this case a pronounced edge is formed which runs parallel with the upper edge of the neck-band and which leaves a narrow connecting portion *d*¹ between the top *b* and the neck-band *a* of three ply thickness in the same manner as in the collar shown in Figs. 1 and 3. It thereby permits the convenient folding of the top over the neck-band in ironing with less effort and pressure than is required in ironing the folding collars heretofore in use.

In the collar shown in Figs. 1 and 3 the narrow connecting-portion between the top and neck-band is made of three plies while the neck-band is made of three and the top of four plies. It reduces the thickness of the narrow connecting portion so as to permit the easy-folding of the top over the neck-band in the same manner as in the construction shown in Figs. 2 and 4.

In manufacturing the collar, the upper part of the top is turned in and stitched to the neckband which will hold the different plies rigidly while the reinforcing seam is made. This will hold the lower part of the top in shape so that it will not stretch while the top is inserted in the band.

The neck-band is provided at its lower outer edge with a narrow auxiliary band *f*

which is stitched at its upper and lower edges to the outer face of the neck-band and which serves for holding the neck-band of the scarf or other neck-wear in the collar for preventing it from slipping down on the neck-band of the shirt or other garment. The auxiliary band forms a raised shoulder that keeps the neck-band of the scarf in place between the neck-band and turned-down top 10 of the collar.

A second auxiliary band or brace *g*, of segmental shape, is stitched on the outer face of neck-band *a*, extending from a point on the upper edge of the same in a curved line below 15 the rear button-hole and up again to another point at the upper edge of the neck-band *a*. It is placed below the auxiliary band *f* immediately below the rear-hole and serves as a brace for strengthening the neck-band and 20 preventing it from being stretched out of shape when washing and ironing the collar.

The advantages of my improved folding collar are that after the collar is ironed the top will hold itself in the proper shape and 25 position near the neck-band and will form by the reinforcing seam running parallel with the upper edge of the neck-band between the top and the neck-band a narrow space in which the neck-band of the scarf can readily 30 slip so as to facilitate the putting on of the same; further that the arrangement of the reinforcing seam being turned in one-quarter of an inch, more or less, at the lower part of the top and being stitched by two rows of 35 stitches to the top will hold the turned-in part perfectly secure between the two lines or rows of stitches and prevent the top-part from being stretched while being inserted 40 into the upper edge of the neck-band and will also prevent its edge from raveling while being laundered. The thinner connecting portion between the top and neck-band facilitates the folding over and the shaping 45 of the top, in ironing and prevents the breaking of the top at the folded edge, while the

reinforcing seam serves as a guide for folding the collar at the right place at the inside of the narrow portion or groove formed between the neck-band and reinforcing seam.

Having thus described my invention, I 50 claim as new and desire to secure by Letters Patent:

1. A folding collar comprising a neck-band of three or more plies, a top of four or more plies, the inner lower part of the top being reinforced by turning in one or more layers and stitching the turned-in portion so as to 55 form a reinforcing seam and a narrow connecting portion of less thickness between the top and neck-band. 60

2. A folding collar comprising a neck-band of three or more plies, a top made of four or more plies and provided at the inner lower part of one of its layers or plies with a turned-in seam connected by two rows of stitches, 65 the remaining layers or plies being inserted into the upper edge of the neck-band and stitched thereto so as to form between the reinforcing seam of the top and the upper edge of the neck-band a narrow connecting 70 portion of less thickness than the top.

3. A collar, the neck-band of which is provided at its outer lower edge with an auxiliary band stitched at its upper edge to the face of the neck-band and forming a shoulder 75 for holding the scarf in place.

4. A collar, the neck-band of which is provided with a segmental auxiliary band or brace extending from a point at the upper edge of the neck-band in a curve below the rear button-hole to a point on the other side 80 and upper edge of the neck-band.

In testimony that I claim the foregoing as my invention, I have signed my name in presence of two subscribing witnesses.

CHARLES I. MANDEL.
